STEAM COLLECTING DEVICE ESPECIALLY
FOR HIGH PRESSURE STEAM

Otto Metzner, Mahrisch-Ostrau, Czechoslovakia

Application March 21, 1935, Serial No. 12,335
In Germany March 21, 1934

7 Claims. (Cl. 122—4)

In steam plants in which the steam collecting pipes are formed as a simple indirect connection of the individual leads, the working offers difficulties inasmuch as when cutting out individual supply leads whole branches of the collecting pipe can be thrown out of action and, as a result of cooling, cannot be kept ready for immediate working. For this reason ring pipes are frequently preferred, but with these the removal of the 10 said difficulties gives rise to other disadvantages.

The invention removes these difficulties in that the ends of the collecting pipes constructed as simple direct connection of the individual leads are connected with the supply or the withdrawal 15 leads by means of auxiliary leads of small diameter. In this way even those branches of the collecting pipes which are thrown out of action owing to the shutting off of supply leads are traversed by a suitable auxiliary flow of steam and 20 are kept at the full working temperature, so that the collecting pipe is always ready for operation throughout its whole length and supply leads which have been shut off can be instantly connected again. In order to ensure that a sufficient 25 flow of steam is attained through the branches in question of the collecting pipes the auxiliary leads are connected with the supply or withdrawal leads preferably only at a place which is removed from their point of attachment to the 30 collecting pipe, or a very small throttling is effected in the supply or withdrawal leads after leaving or entering the auxiliary leads. At the junction of the auxiliary leads with the withdrawal leads preferably a nozzle-like slight construction is provided in the same, at the narrowest 35 place of which the auxiliary leads then open into the withdrawal leads.

In the accompanying drawing several forms of the invention are shown by way of example with 40 reference to steam boiler plants.

In the plant according to Figure 1 five boilers 1 are connected to a collecting pipe 3 by means of leads 2, the said pipe 3 directly connecting together the five separate leads 2 in a simple pipe line. Two withdrawal leads 4 lead from the collecting pipe 3 to the two turbines 5 with the main 45 stop valves 6.

If now in such a plant only one turbine and the two boilers nearest to it are in operation, then 50 the whole of the remaining part of the collecting pipe 3 has no steam passing through it and it cools down. If then one of the other boilers is to partake in the driving, this cannot be done immediately.

55 In order to avoid this drawback the ends of

the collecting pipe 3 are connected by means of an auxiliary lead 7, which need have only a comparatively very small diameter, to the withdrawal leads 4, and the collecting pipe 3 with the auxiliary lead 7 forms a ring, connecting conduits 8 leading from the auxiliary lead 7 to the withdrawal leads 4 parallel to the latter. These auxiliary connecting conduits 8 open into the withdrawal leads 4 only at a position which is removed from the opening of the same from the collecting pipe 3, and in fact only behind the shut-off member 6, so that there is first a certain pressure fall before the auxiliary leads 7 and 8 enter the main pipes 3 and 4 and the flow through the auxiliary leads 7 and 8 is ensured. Small shut-off members 9 are installed in the auxiliary connecting conduits 8. These can serve for warming up the withdrawal leads 4 and the turbines 5 as well as a by-pass valve for actuating the shut-off valves 6 in the main pipes when setting the plant 20 into operation.

Besides these shut-off members 9 in the auxiliary connecting conduits 8 there are also closing members 10 in the auxiliary lead 7 lying parallel to the collecting pipe 3 between the ends of the 25 collecting pipe 3 and the auxiliary connecting conduits 8. These are constructed so that even in the closed position they still allow a small quantity of steam to pass through.

In the case just described, therefore, there is a 30 flow even in the branch of the collecting pipe 3 which is not traversed by the main flow of steam, and the collecting pipe 3, therefore, is always at its full temperature throughout the whole extent. In that branch of the auxiliary lead 7 which adjoins the part of the collecting pipe 3 traversed by the main flow of steam, the valve 10 is then closed, but as a result there is still a small flow in this part of the auxiliary lead 7.

Figure 2 shows the same arrangement only 40 with the difference that the auxiliary lead 7 connects the ends of the collecting pipe 3 not with the withdrawal leads 4, but with the supply leads 2. Correspondingly, the auxiliary branch conduits 8 are branched off from the supply leads 2 45 at a place removed from the point of attachment of the same to the collecting pipe 3 and in fact in front of the shut-off members 6 in the supply leads 2.

Figure 3 of the drawing shows a plant in which 50 the boilers 1 are arranged in two series and the collecting pipe 3 has a horse-shoe shape. In this case auxiliary leads 7 are disposed parallel to the two shanks of the collecting pipe 3, said leads proceeding from the dead ends of the collecting 55

pipe 3 and opening into the withdrawal lead 4. In the withdrawal lead 4 there is a nozzle-like slight construction 11, and at the narrowest part of the same the auxiliary leads 7 are attached to the withdrawal lead 4. These places of attachment are arranged in front of the main shut-off member 6. Of course the point of attachment may also be arranged behind the shut-off member 6, but then a shut-off member would have to be inserted again in the auxiliary connecting conduit.

The arrangement according to the invention is particularly advantageous for high pressure lines and for lines for superheated steam.

15. What I claim is:

1. A steam collecting pipe system especially for high pressure steam plants comprising a steam collecting main, branch pipes for the supply of the steam and at least one branch pipe for the withdrawal of the steam, the steam collecting main forming a simple direct connection for the individual supply and withdrawal branch pipes, and auxiliary leads of smaller diameter than the collecting main connecting the ends of the latter with at least one of the said branch pipes and forming rings with the steam main.

2. A steam collecting pipe system especially for high pressure steam plants comprising a steam collecting main, a series of branch pipes for the supply of the steam and another series of branch pipes for the withdrawal of the steam, the steam collecting main forming a simple direct connection for the individual supply and withdrawal branch pipe and auxiliary leads of smaller diameter than the collecting main connecting the ends of the latter with one series of the said branch pipes and forming rings with the steam main.

3. A steam collecting pipe system according to

claim 1 characterized therein that the connecting points of the auxiliary leads with the branch pipes are positioned remote from the connecting points of the branch pipes with the steam collecting main.

4. A steam collecting pipe system according to claim 1 characterized by shut-off members being inserted in the auxiliary leads and being constructed so as to allow a limited flow even in their closed state.

5. A steam collecting pipe system according to claim 1 characterized by valves being capable of creating a slight throttling action being inserted in the branch pipes between the connecting points of the latter with the steam collecting main and with the auxiliary leads.

6. A steam collecting pipe system according to claim 1 characterized by stop valves being provided in the branch pipes and stop-valves being provided in the auxiliary leads, the latter serving at the same time as by-pass valves for the stop-valves in the branch pipes.

7. A steam collecting pipe system especially for high pressure steam plants comprising a steam collecting main, branch pipes for the supply of the steam and at least one branch pipe for the withdrawal of the steam, the steam collecting main forming a simple direct connection for the individual supply and the withdrawal branch pipe and auxiliary leads of smaller diameter than the collecting main connecting the ends of the latter with the withdrawal branch pipe and forming rings with the steam main, a nozzle like contracting device being inserted in the withdrawal branch pipe, the auxiliary leads entering said contracting device at the point of its smallest cross-section.
